(57) **CLAIM**

The ornamental design for a camping cabin, as shown and described.

DESCRIPTION

FIG. 1 is a front, top and left side perspective view of a camping cabin according to the invention;

FIG. 2 is a front, top and right side perspective view thereof;

FIG. 3 is a rear, top and right side perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is a front, bottom and right side view thereof; and,

FIG. 11 is a rear, bottom, left side view thereof.

The broken lines and stippling shown in the Figures are included to show unclaimed subject matter only and form no part of the claimed design.

1 Claim, 11 Drawing Sheets
